UNITED STATES PATENT OFFICE

2,209,814

ELECTRICAL CONNECTOR

Clinton H. Finger, Milford, Conn., assignor to
 General Electric Company, a corporation of
 New York

Application February 6, 1940, Serial No. 317,515

1 Claim. (Cl. 173—322)

My invention relates to electric cord sets provided with detachable plug connectors of the type commonly used with electric household appliances.

5 An object of my invention is the provision of improved means for protecting the connection of the conductors of the cord set to the plug connector.

In the accompanying drawing, Fig. 1 is a view 10 of the interior of a plug connector showing a strain relief means for securing an electric cord to the body of the connector; Fig. 2 is a perspective view, partly in section, of the strain relief means; Fig. 3 is a perspective view of the plug 15 connector; and Fig. 4 is a perspective view of a portion of the strain relief means.

Referring to the drawing, my plug connector 10 includes a housing 11 of insulating material, such as a phenolic condensation product and 20 filler. The housing is formed in two parts of identical size and shape. The interior of one-half of the housing is shown in Fig. 1 and is formed with spaced recesses 12 merging with an opening 13 at one end for receiving an electric 25 cord and associated strain relief means, the other end being provided with slots 14 for receiving the connector prongs of an electric appliance. A contact structure 15 is seated in each of the recesses 12 for making electrical contact with the 30 appliance prongs, each contact being formed of opposed spring blades secured together at one end and provided with a terminal screw 16. The contacts float freely within the recesses 12 to compensate for slight variations in the spacings 35 of the appliance connector prongs. The two parts of the housing are held together in assembled relationship by any suitable fastening means, such as the screws 17, which extend through the housing at points between the contacts.

40 An electric cord 18 extends through the opening 13 and is electrically connected to the plug connector; the cord comprises two insulated conductors 19 protected by an overall sheath 20 of fibrous insulating material, such as a cotton or rayon braid. The ends of the individual conductors are stripped, as shown at 21, and are fastened to the contacts by the terminal screws 16.

50 In cord sets of the type described it is important that the electric cord be secured to the connector in a manner such that strains or pulls on the cord will not be transferred to the electrical connection between the conductors and the 55 connector which result might seriously impair

or destroy the usefulness of the cord set. Moreover, the conductors of the cord should be protected in such a manner that they cannot become twisted or damaged within the body of the connector, or at the point where they enter the 5 connector, in such a manner as to cause short circuits.

To this end, I provide an insulating rubber sleeve 22 around the end of the electric cord at the point where it enters the housing 11. In manufacture, the sleeve may be molded directly around the cord, or otherwise secured thereto, and is formed of flexible or resilient rubber. The sleeve 22 is provided with a perimetrical flange 23, which rests within a corresponding groove 24 15 formed in the wall of the opening 13, so that longitudinal movement between the sleeve and insulating housing is prevented. This means that any pulls on the cord will be transmitted by the rubber sleeve to the housing of the connector and will not be transferred to the connection of the conductors with the contacts 12. A flexible portion of the sleeve extends in tapered 20 formation along the length of the cord and protects the cord from kinks or sharp bends at the 25 point where it enters the body of the connector.

Relative movement between the rubber sleeve and the electric cord is prevented by placing a tie member 25 within the rubber sleeve 22 and by winding the individual conductors 19 around the 30 member. This is of particular advantage in those cases where the outer sheath of the electric cord is of fibrous material which does not bond easily to the rubber sleeve during vulcanization of the latter. However, by this construction an effective bond is secured between the conductors and the sleeve inasmuch as the tie member is embedded immovably within the rubber sleeve. By utilizing this construction, cord sets will withstand a pull of approximately fifty pounds between the cord and the body of the plug. 35

The member 25 is disposed transversely of the rubber sleeve, as shown most clearly by Figs. 1 and 2, and is located at a point substantially in alignment with the flange 23, so that any stress 45 placed on this member is transferred to the sleeve and from the latter, through the medium of the flange 23, to the connector. The member 25 may be provided with spaced pairs of grooves 26 for receiving the individual conductors to keep them 50 separate from one another. In those cases where the bared ends of the conductors are wound around the member, the latter may be formed of any suitable insulating material, such as wood or sheet fiber. 55

In some existing constructions, transverse tie members have been disposed within connector housings, and insulated conductors wrapped around them to absorb pulls on the electric cord; 5 however, as far as I know, the use of a tie member in combination with a protecting rubber sleeve is new and provides advantages not attained with former constructions. Inasmuch as the tie member is embedded within the insulating rubber sleeve, the conductors may be stripped 10 of insulation before being wrapped around the member thereby reducing the overall size of the assembly. Moreover, they cannot become unwrapped from the tie member being held in place 15 by the rubber sleeve. This is of advantage if the plug is taken apart for repair since the strain relief is not disassembled. There is no danger of the bared wires 21 becoming twisted or dislocated in a manner to cause a short circuit of the connector. Since the tie member 25 is preferably 20 made of insulating material, such as sheet fiber, the surrounding rubber sheath protects it from heat incident to the use of the connector on an electric appliance, such as an iron or toaster. 25 By placing the tie member within the rubber sleeve a more compact structure is to be had inasmuch as space is not taken up by this member within the body of the housing. The rubber sleeve and tie member 25 are assembled as a 30 unit by molding the rubber sleeve around the member at the same time that it is molded to the cord 18; this means that these elements may be mounted as a unit within the housing thereby 35 effecting a considerable saving in the cost of assembling the device.

My invention is particularly applicable to those cord sets in which an electric cord having a fibrous jacket is applied to the plug since it is difficult to attain a good frictional bond between the rubber sleeve and the jacket of the cord. 5 However, it should be manifest that the invention is applicable equally as well to cord sets utilizing cords having other forms of insulating jackets such as all rubber jackets, although in such instances a good bond can be secured between the rubber jacket and sleeve during vulcanization of the latter to supplement the action 10 of the tie member 25.

What I claim as new and desire to secure by 15 Letters Patent of the United States is:

In a plug connector, a housing of insulating material having an opening at one end, contact means within said housing for receiving the connector prongs of an electric device, an electric cord extending through said opening, the individual conductors of said cord being connected to corresponding contact means, a flexible resilient rubber sleeve surrounding and engaging said electric cord and being disposed in the opening 20 in said housing, said sleeve having a flexible portion extending outwardly from said housing along said electric cord, cooperating means on said sleeve and housing to prevent relative longitudinal movement therebetween, and a tie member 25 embedded in and extending transversely of said rubber sleeve, the individual conductors of said electric cord being wrapped around said tie member to prevent relative sliding movement between 30 said sleeve and said electric cord.

CLINTON H. FINGER.
